UNITED STATES PATENT OFFICE.

ALBERT DEWEY TOMLINSON, OF BOSTON, MASSACHUSETTS.

SOFA-BED.

SPECIFICATION forming part of Letters Patent No. 643,210, dated February 13, 1900.

Application filed October 6, 1899. Serial No. 732,776. (No model.)

To all whom it may concern.

Be it known that I, ALBERT DEWEY TOMLINSON, a citizen of the United States, residing at Boston, county of Suffolk, State of Massachusetts, have invented an Improvement in Sofa-Beds, of which the following description, in connection with the accompanying drawings, is a specification, like letters and numerals on the drawings representing like parts.

10 This invention relates to a sofa folding bed, the object of the invention being to provide a combination piece of furniture of this character which is simple in construction and which can be opened and closed with facility 15 and rapidity, it being adapted when open to serve as a bed and when closed as a sofa or couch, and the organization is such that when closed the article will contain and hide the bedclothing and when opened the mattress 20 supporting structure will not present any obstruction, as in such a case as this said obstruction would be decidedly uncomfortable to the user of the device when the same is employed as a bed.

25 The improved device includes as one of its features a frame consisting of a bottom piece and a top piece hinged thereto, and contains a mattress-supporting structure foldable along its middle and extending continuously 30 from the side board of the top piece to the side board of the bottom piece, and a cross-rail uniting the end members of the bottom piece, but not sustaining said mattress-supporting structure. The cross-rail serves not only to 35 strengthen the bottom piece against longitudinal strains, but serves a like function for the top piece, and as it is located below the mattress-supporting structure it cannot come in contact with the latter, so that such structure presents upon its upper side a smooth and 40 unbroken surface.

In the drawings, Figure 1 is a perspective view of a combination sofa and bed constructed in accordance with my invention in 45 a simple embodiment thereof and representing the same as open and showing it as provided with a woven-wire structure to sustain a mattress. Fig. 2 is a similar view showing the mattress in place. Fig. 3 is a like view 50 showing the article as closed; and Fig. 4 is a perspective view of the same upholstered or covered, but without a back.

The sofa-bed illustrated in Figs. 1, 2, and

3 includes in its construction a frame, which may be made from any suitable material. The 55 frame shown is indicated by 12, and it is rectangular in shape and consists of two main sections, as A and B. The part A constitutes the bottom piece and the part B the top piece, and the two sections are connected in such a 60 manner that the part B can be shifted relatively to the part A to open and close the same. The bottom piece or body is provided at its corners or at other convenient places with the depending legs C, adapted to rest 65 upon a floor when the back is down, while the back 13 of the top piece is furnished at its opposite outer corners with projecting portions 14 and 15, adapted when the top piece is down to rest upon the floor and serving as 70 legs to support said top piece, and it will be seen that when the top piece is down the upper edges of the two parts are in the same horizontal plane, whereby the bed can be readily entered from either side or the end. 75 The back 13 is in the nature of a side board, the complementary side board being denoted by 16 and being disposed in parallelism therewith. The end pieces of the upper sections are denoted by 17 and 18, while the substantially similar end pieces of the bottom part are denoted by 20 and 21, and the coöperating end pieces fit substantially edge to edge when the top piece is down and they are united by 80 hinges, as b, mounted upon the upper sides 85 thereof and countersunk therein. The end pieces 20 and 21 are united at the forward side thereof by a center rail 22, shown as located some distance below the upper edge of the bottom piece or body and secured between 90 and suitably to the inner faces of said end pieces, the purpose of said rail being to 95 strengthen the structure against longitudinal strains.

The sofa-bed is provided with a mattress-supporting structure, preferably formed from woven spring-wire and foldable at about its middle on a line extending longitudinally of the bed and in parallelism with the side pieces, and it is free at its middle, so that it may be 100 shaped to adjust itself readily to the central fold of a mattress, as illustrated in Fig. 3, and it will be evident by virtue of this that the fold is a smooth one, without any angles, and that it is decidedly comfortable to the limbs, 105 and the center rail usually present at this

place is wholly dispensed with and but a single one employed. The center rail 22 is substantially narrow throughout its entire length; but its ends are widened at 30 and 31, 5 and such widened portions fit against the inner flat faces of the end pieces 20 and 21, so as to materially strengthen the same depthwise thereof. It will be seen upon examination of said figure that the center rail 22 is 10 located below the mattress-supporting structure G, and hence it does not support the same, as in such a case as this the rail would form an objectionable body in the middle 15 of the mattress, which would be uncomfortable.

By the construction specified I can simply lay a thin quilt upon the structure G when the same is unfolded without annoyance to the sleeper, as the body does not come in contact with the center rail. This center rail therefore in no wise sustains the mattress-supporting structure, but is employed solely as a brace for the bottom piece against endwise strains thereof.

25 The mattress-supporting structure is located, preferably, some distance below the upper edges of the two parts of the bed when the same is opened, so that when said bed is closed it can easily receive a mattress and 30 bedclothing, as F.

The mattress-supporting structure, it will be seen, Fig. 1, extends continuously between the side boards 13 and 16, but it is preferably free of the same, it being connected to the 35 end pieces. Said structure G is secured at one end by means of clamps, as f, to the end pieces 17 and 20, while the opposite end of said structure is adjustably connected to the end pieces 18 and 21, by reason of which any 40 looseness or slack that may be present in the same may be readily taken up. The clamps d are secured by means of tie-bolts, as c, to the end pieces 18 and 21. Each of the clamps consists of two superposed plates or flat bars, 45 (see Figs. 1, 2, and 3,) between which the end of the mattress is gripped and held by the fastening-bolts e. By turning the nuts 32 of the tie-bolts toward the right the clamps d can be drawn toward the parts 18 and 21 for 50 the purpose of tightening the structure or spring-bottom G. It will therefore be seen that not only the sides of the mattress are 55 free, but the same is free longitudinally thereof along its middle, so that a fold can be made therein, as shown in Fig. 3, when the article is shut, whereby said structure can readily shape or accommodate itself to the curvature or conformation of the contained mattress along the fold thereof, the clamps d, 60 secured to the respective parts 18 and 21, being separated a distance sufficient to insure this result.

The piece of furniture thus described may be upholstered to any suitable extent, and 65 the upper side of the flat mattress-supporting structure forms a strong support for cushions placed thereupon, and as the same is free at

its sides and also at its middle it is highly flexible at all places between its ends, which is a decided point of utility.

The invention is not limited to the precise details herein set forth, for they may be variously modified within the scope of the accompanying claims.

Having fully described my invention, what 75 I claim as new, and desire to secure by Letters Patent, is—

1. A sofa-bed comprising a frame consisting of a bottom section and a top section foldable upon said bottom section, and only one 80 of which has a center rail and said center rail being secured to the end pieces of the bottom section and serving to brace the same longitudinally and being adjacent to the inner open side of the top section to also brace the 85 latter longitudinally, and a continuous flexible mattress-supporting structure secured to the end pieces of said two sections relatively remote from the upper edges thereof when the bed is open, and located above and out of contact with said center rail, and said means which secure the ends of the mattress to the 90 end sections being superposed and at remote distances from each other when the sofa-bed is closed, and being separated laterally at opposite sides of a longitudinal median line of the mattress when the bed is open, whereby when said structure is folded, it will present a rounded surface at the forward side thereof and whereby it constitutes a receptacle for 95 bedclothing.

2. A sofa-bed comprising a frame consisting of a bottom section and a top section foldable upon said bottom section, and only one 105 of which has a center rail, and said center rail being secured to the end piece of the bottom section and serving to brace the same longitudinally and being adjacent to the inner open side of the top section, to brace the same longitudinally, clamps arranged in pairs and 110 secured to the end pieces of the two sections, two of said clamps at one end of the bed being adjustably connected thereto and being disposed relatively remote from the upper edges of the two sections when the bed is 115 open, and a continuous flexible mattress-supporting structure secured between the jaws of the clamps and the portions of the clamps at the opposite ends of the bed being superposed and at remote distances from each other 120 when the bed is closed, and being separated laterally at opposite sides of a longitudinal median line of the mattress when the bed is open, whereby when the latter is folded it will present a rounded surface at the forward side 125 thereof and whereby it constitutes a relatively-deep receptacle for bedclothing.

In testimony whereof I have signed my name to this specification in the presence of two subscribing witnesses.

ALBERT DEWEY TOMLINSON.
